UNITED STATES PATENT OFFICE.

THEODORE C. PROUTY AND WILLIS O. PROUTY, OF HERMOSA BEACH, CALIFORNIA, AS
SIGNORS, BY MESNE ASSIGNMENTS, TO AMERICAN ENCAUSTIC TILING COMPANY,
LTD., OF LOS ANGELES, CALIFORNIA, A CORPORATION OF NEW YORK.

PROCESS OF MAKING TILE.

Application filed March 7, 1925. Serial No. 13,887.

The purpose of our invention is the production of dry-pressed tiles so formed that each tile presents the appearance of a composite structure built up of separate pieces 5 of different colors assembled to form any selected design. Efforts have heretofore been made to produce such a product using plastic mixtures for the bisque, but mixtures that are plastic or that can be poured do not preserve their form with sufficient precision in firing to give a product reproducing with sufficient fidelity the appearance 10 of a design consisting of assembled varicolored pieces. Furthermore plastic mixtures are not adapted to the rapid and precise formation of the original design with such uniformity and rapidity as is necessary for the production of ornamented tile in quantity and at a low cost. In the process 15 of molding dry bisque mixtures the mixture is subjected in the mold to a pressure of several hundred pounds per square inch. With this pressure I have found it possible to impress any desired design in recessed 20 lines on the face of the tile and that a design so impressed is perfectly preserved in the fired bisque. I then apply glazes of different colors to the areas defined by the recessed lines, this operation, of course, being performed by hand. The tile is then 25 fired in the glaze kiln, thus producing a tile bearing a design formed by separate areas of different colors separated by recessed lines. Subsequently the recessed lines or 30 grooves are filled with cement thus producing the exact appearance of joints between the areas of different colors, and the visible part of the finished product differs in no respect from a design formed by assembling 35 and cementing together separate pieces of different colors. The grooves may be filled by simply applying a mass of cement to the face of the tile and then wiping off the surplus. The part of the cement which has 40 been pressed into the grooves will remain when the surface of the tile is wiped. The design formed upon each tile may be either in itself a complete and separate ornamental configuration or it may be part of a larger 45 pattern extending over a number of tiles.

In the drawing:

Figure 1 represents a dry-molded tile as it comes from the molding press and bearing a design outlined in recessed lines.

Figure 2 is a cross section on the line 2—2 of Figure 1. 55

Figure 3 is a face view of the finished tile showing the recessed lines filled with cement.

Figure 4 is a section on line 4—4 of 60 Figure 3.

Figure 5 shows the application of my invention to a paneled wainscoting in which the complete design of the panels is made up of parts borne by separate tiles embodying 65 my invention.

Figure 6 consists of views of four tiles bearing the designs which are assembled to form the panels shown in Figure 5.

Figure 7 is a view of a multiple tile, that 70 is a large sheet or slab of tiling of the thickness of tiles of the usual size and having upon its surface lines formed by my process, these lines representing the configuration of tiles of the size and form heretofore used. 75

The double lines, B, in Figure 1 represent the recessed lines or grooves which define the outline of the design on the dry pressed tile as it comes from the molding press. The die by which the design is impressed upon 80 the dry bisque mixture is formed in raised lines thereon. The die may be made by simply cutting the design in intaglio in some soft metal or other material such as plaster or papier mâché and then using the intaglio 85 design so formed as a mold from which to cast the die in any suitable metal as brass or type-metal. The recessed lines or grooves, B, may be made of suitable depth to hold the cement and of such width as to 90 accurately simulate a joint between separate pieces. In the design illustrated if the area C were made black, the areas D red and the remainder, E, of the face of the tile white the appearance of the finished tile would be 95 identical with that of a design formed by assembling and cementing together separate pieces of these colors.

In Figure 5 we have shown a paneled wainscoting. In the construction of wainscoting of this type from the materials and by the methods heretofore used it has been necessary for the tile setter to cut the tiles in the positions designated by the letters G, H and I in order to reduce them to the dimensions necessary to receive the sections of frieze-strip F, the strips F being separate pieces of tile of the form and size necessary 100 105

to form the panel desired. The cutting of the tile and manufacturing and setting the separate frieze strips are a source of increased cost, which cost is increased by the 5 breakage incident to cutting the large number of tiles of reduced dimensions necessary for a panel design of this type. By our invention the manufacture of the four special tiles shown in Figure 6 renders it possible 10 to produce the paneled wainscot shown in Figure 5 without cutting any of the tiles and with no extra operation on the part of the tile-setter other than merely selecting the right tiles to make the outline of the 15 panels. The corner tile having the right-angle panel band, the tile having the panel band at one side and those for narrow panels having the band on three sides and on two opposite sides are all of standard size, 20 i. e., the same in dimensions as the plain tile appearing in the wainscot. The band is formed by pressing a recessed line or groove into the tile in the molding press and after firing applying the desired colors 25 of glaze inside and outside of the line. The outline of the panel is not, of course, limited to a flat band of one color, but may be divided into squares of different colors, or a border design of any form may be used. In 30 fact designs of any kind, panels or otherwise, that spread over a number of tiles may be formed as above described, and any of the designs so formed present the appearance 35 of being assembled from separate pieces. The depth of the grooves should be not substantially less than their width and the glaze mixture should be so applied that it will not enter the grooves.

A further field of usefulness for my invention is illustrated in Figure 7, which represents 40 an area that would ordinarily be covered by a considerable number of tiles,

depending on the size used. Tiles six inches square are the largest now in common use. By the use of my invention the entire area 45 represented in Figure 7 can be covered by a single large tile bearing recessed lines filled with cement and perfectly simulating eighteen separate square tiles, thus greatly reducing the cost of setting the tile. 50

In order to provide against non-adherence of the cement by reason of the glaze being permitted to enter the grooves the cement may be mixed with water having sodium silicate in solution, or adherence of 55 the cement may be secured by similarly using a suitable proportion of any of the adhesives suitable for glass or porcelain, or such substances may be applied to the grooves after the glaze has been fired and 60 before filling them with cement.

We claim:

The process of making an integral multiple tile body having the appearance of an assemblage of a plurality of tiles, which 65 comprises the operations of molding under pressure a dry bisque mixture by means of dies of the form of the desired multiple tile body and one of said dies having thereon a relief design outlining the forms of a plurality of separate tiles and adapted to form 70 grooves in the face of the multiple tile body, firing the multiple tile body so formed to produce the bisque, applying glaze mixture to the areas of said bisque between and 75 defined by said grooves, again firing said tile body bearing the glaze mixture so applied, and subsequently filling said grooves with cement.

In testimony whereof, we have subscribed 80 our names.

THEODORE C. PROUTY.
WILLIS O. PROUTY.
